NUTCRACKER

Robert D. Wehr, 4705 Arcadia Road,
Tarpon Springs, Fla. 33589

Filed Apr. 4, 1973, Ser. No. 347,791

Term of patent 14 years

Int. Cl. D7—06

U.S. Cl. D7—98

FIG. 1 is a top perspective view of a nutcracker embodying my new design:

FIG. 2 is a front elevation thereof:

FIG. 3 is a top view thereof:

FIG. 4 is a bottom view thereof:

FIG. 5 is an end view thereof as seen from the right of FIG. 2; and

FIG. 6 is a cross-sectional view thereof taken generally along line 6—6 of FIG. 2.

I claim:

The ornamental design for a nutcracker, substantially as shown.
